(57) **CLAIM**

The ornamental design for a clothing set with lifting and access features as shown and described.

DESCRIPTION

FIG. 1 is a front elevation view of a clothing set with lifting and access features, showing my new design;

FIG. 2 is a back view thereof;

FIG. 3 is a right side elevational view thereof;

FIG. 4 is a top elevational view thereof;

FIG. 5 is a bottom elevational view thereof;

FIG. 6 is a front elevational view with the access portions in an open state;

FIG. 7 is a right side elevation view with the access portions in the open state with the left side elevational view being a mirror image of the right side elevation view; and,

FIG. 8 is a cross sectional view taken from FIG. 3.

The even-dash broken lines in the drawings represent stitching and environment forming no part of the claimed design. The appearance of the cross hatched wavy shaded areas throughout the drawings are included to indicate a contrast in materials and do not form part of the claim.
